(57) **CLAIM**

We claim the ornamental design for a drinking container, as shown and described.

DESCRIPTION

FIG. 1 is a top perspective view of a drinking container, showing our new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The outer wall broken line ring in FIGS. 1 and 3-7 represents a seam line. The remaining broken lines in the drawings depict portions of the drinking container that form no part of the claimed design.
